Copending U.S. Appl. No. 29/405,784, filed Nov. 7, 2011.

Primary Examiner — John Windmuller

(74) *Attorney, Agent, or Firm* — Dennis J. Williamson;
Moore & Van Allen PLLC

(57) **CLAIM**

We claim the ornamental design for a mop frame, as shown and described.

DESCRIPTION

FIG. 1 is a front view showing our new design for a mop frame;

FIG. 2 is a back side view showing our new design shown in FIG. 1;

FIG. 3 is a left side view showing our new design shown in FIG. 1;

FIG. 4 is a right view showing our new design shown in FIG. 1;

FIG. 5 is a perspective view showing our new design shown in FIG. 1;

FIG. 6 is a top view showing our new design shown in FIG. 1; and,

FIG. 7 is a bottom view showing our new design shown in FIG. 1.

The portions shown in broken lines are not part of the claimed design but show the environment in which the design is associated.

1 Claim, 7 Drawing Sheets
